SHIPPING PACK

Filed Oct. 22, 1923

FIG. 1

Inventor
John J. Beaton

By *Des Spears*
Attorney

UNITED STATES PATENT OFFICE.

JOHN J. BEATON, OF WAREHAM, MASSACHUSETTS.

SHIPPING PACK.

Application filed October 22, 1923. Serial No. 669,951.

To all whom it may concern:

Be it known that I, JOHN J. BEATON, a citizen of the United States, residing at Wareham, county of Plymouth, Commonwealth of Massachusetts, have invented certain new and useful Improvements in Shipping Packs, of which the following is a specification.

In this application the invention involved has to do with the packaging of such small fruits as cranberries for the purpose of shipment and sale and particularly to a package or pack where it is desired to have the berries visible but reasonably inaccessible.

In my previous application I discussed my invention more particularly with reference to a package filled through the top and deliberately left open for ventilation and inspection but under certain circumstances for certain parts of the trade, it is desirable to combine this with a transparent closure for the opening.

In accordance with my invention this closure is not a tight or air proof closure and the ventilation is maintained. The top filling is also maintained all without loss of the advantages of my original pack and without material addition to expense either in material or labor. In the accompanying drawings I have shown a simple form of my invention which I will discuss, utilizing like reference characters to indicate corresponding parts. In these drawings:—

Fig. 1 is a sectional view of a pack in accordance with my invention.

Fig. 2 illustrates the initial filling step. Fig. 3 a second settling step.

Fig. 4 the covering step, and

Fig. 5 the ultimate closing.

The pack shown in Fig. 1 consists of an open top container 10 with surrounding shell 11 slidably mounted on the sides of the container and a narrow flange 12 about the top of the surrounding shell defining the filling and display aperture through which the berries B are introduced as shown in Fig. 2. When the proper weight of berries has been introduced into the container the surrounding shell 11 is pushed down so that the flanges 12 press upon the margins of the container and the surface of the berries contained therein giving to them a very slight settling pressure and equalizing their distribution over the surface. This insures the filling of the corners and

sides while generally leaving the central portion slightly above.

The package is now of known weight and to all practical purposes uniformly packed so that a minimum of settling will result. In the next step I raise the shell 11 slightly as shown in Fig. 4, and tuck under the edges of the flange 12 the margins of a transparent sheet of thin pliable material such as the transparent papers of commerce. The paper P so introduced conforms to the surface of the berries in general but leaves a variety of creases and folds which provide ventilation out from under the edges of the flange 12 or through apertures 12¹ formed in the flange for that purpose. If desired, the covering sheet P may itself be provided with a plurality of relatively small ventilating holes P¹ to insure adequate ventilation through the center of the container.

The flange 12 will continue to follow down any subsequent settling of the berries, and the transparent sheet at all times conforming to the surface, exposes the berries to inspection as in a frame, thus adding materially to the artistic appearance.

While the method defined is a convenient and expeditious manner of packing, it may obviously be varied and within the limits of my invention details of the package and sheet may be somewhat departed from and all without departing from the spirit of my invention as defined in the claims.

What I therefore claim and desire to secure by Letters Patent is:—

1. A unitary pack comprising a rectangular open top container and a surrounding shell slidably mounted thereon, and having a narrow flange at its upper edge adapted to overlie the margins of the container top and to have continuous progressive bearing on the contained fruit adjacent the margins of the container, a predetermined weight of berries disposed in said pack through the opening defined by said flange, and a flexible transparent sheet inserted over the top of the berries and having its edge tucked beneath said flange, said flanges having ventilating apertures formed therein.

2. A unitary pack comprising a rectangular open top container and a surrounding shell slidably mounted thereon, and having a narrow flange at its upper edge adapted to overlie the margins of the container

top and to have continuous progressive bearing on the contained fruit adjacent the margins of the container, a predetermined weight of berries disposed in said pack through the opening defined by said flange, and a flexible transparent sheet inserted over the top of the berries and having its edge tucked beneath said flange.

3. A unitary pack comprising a rectangular open top container and a surrounding shell slidably mounted thereon, and having a narrow flange at its upper edge adapted to overlie the margins of the container top and to have continuous progressive bearing on the contained fruit adjacent the margins of the container, a predetermined weight of berries disposed in said pack through the opening defined by said flange, and a flexible transparent sheet inserted over the top of the berries and having its edge tucked beneath said flange, said flanges having ventilating relation thereto.

4. The method of packing cranberries or

the like consisting in providing an open top container and a surrounding shell slidably mounted thereon, and having a narrow in-turned flange at its upper edge adapted to overlie the margins of the container top and to have continuous progressive bearing on the contained berries adjacent the margins of the container, in introducing a predetermined weight of berries through the opening defined by said flange margins, in settling the berries, in raising the shell and in introducing a flexible transparent sheet into the pack and over the surface of the berries with its margins beneath said flange and in sliding down the shell to bring said flange in contact with the sheet margins and press the same on the berries.

In testimony whereof I affix my signature in presence of two witnesses.

JOHN J. BEATON.
